US0D1008281S

(12) United States Design Patent (10) Patent No.: US D1,008,281 S
(45) Date of Patent: * Dec. 19, 2023

(54) DISPLAY SCREEN OR PORTION THEREOF
WITH A SET OF GRAPHICAL USER
INTERFACES

(71) Applicant: Apple Inc., Cupertino, CA (US)

(72) Inventors: Gary Butcher, San Jose, CA (US);
Alan C. Dye, San Francisco, CA (US);
Aurelio Guzmán, San Jose, CA (US);
Brian Andrew Schmitt, San Francisco,
CA (US); Wan Si Wan, Sunnyvale, CA
(US)

(73) Assignee: Apple Inc., Cupertino, CA (US)

() Term: 15 Years

(21) Appl. No.: 29/751,405

(22) Filed: Sep. 21, 2020

Related U.S. Application Data

(63) Continuation of application No. 29/681,373, filed on Feb. 25, 2019, now Pat. No. Des. 896,821, which is a continuation of application No. 29/628,359, filed on Dec. 4, 2017, now Pat. No. Des. 841,664, which is a continuation of application No. 29/583,589, filed on Nov. 7, 2016, now Pat. No. Des. 804,523, which is a continuation of application No. 29/540,778, filed on Sep. 28, 2015, now Pat. No. Des. 775,150, and a continuation of application No. 29/540,798, filed on Sep. 28, 2015, now Pat. No. Des. 771,128, which is a continuation of application No. 29/501,109, filed on Sep. 1, 2014, now Pat. No. Des. 772,284, said application No. 29/583,589 is a continuation of application No. 29/501,109, filed on Sep. 1, 2014, said application No. 29/540,778 is a continuation of application No. 29/501,109, filed on Sep. 1, 2014.

(57) CLAIM

The ornamental design for a display screen or portion thereof with a set of graphical user interfaces, as shown and described.

DESCRIPTION

The FIGURE is a front view of a display screen or portion thereof with a set of graphical user interfaces showing the claimed design.

The broken lines in the FIGURE show a display screen or portion thereof, and form no part of the claimed design.
The set of graphical user interfaces of the FIGURE is arranged relatively on the drawing sheet for the convenience of illustration and the relative positioning forms no part of the claimed design.

1 Claim, 1 Drawing Sheet
